UNITED STATES PATENT OFFICE.

HENRY H. CUMMINGS, OF NEWTON, MASSACHUSETTS.

LACING.

No. 851,073.

Specification of Letters Patent.

Patented April 23, 1907.

Application filed January 19, 1906. Serial No. 296,812.

To all whom it may concern:

Be it known that I, HENRY H. CUMMINGS, a citizen of the United States, residing at Newton, in the county of Middlesex and State of Massachusetts, have invented an Improvement in Lacings; of which the following description, in connection with the accompanying drawings, is a specification, like letters on the drawings representing like parts.

My invention relates to lacings and particularly to means for improving the stiffening of lacing ends.

In stiffening the ends of lacings it has been a frequent custom to use a metal stiffening member about which the fabric of the lacing is rolled or wrapped, so that the resultant stiffened end comprises a metal stiffening member within and covered by the textile material of the lacing itself. Lacings having covered stiffeners of this character, even where a portion of the extreme end of the lacing has been folded within the stiffening member with a view to preventing the tip of the lacing from unraveling, nevertheless through wear tend to fray and present an unsightly appearance. Furthermore, the fabric covering of the tip does not so well assist in finding the eyelets when the lacing is being laced, as does a metal or other hard tip or covering.

My invention contemplates, among other objects, the provision of a lacing end having an interior stiffening member and presenting all the advantages of durability, construction and appearance which is offered by lacings of this type, while at the same time provided with a tip of metal or other hard, dense material, so that the disadvantages of an end tipped with textile fabric are practically obviated.

My invention will be best understood by reference to the following specification, when taken in connection with the accompanying illustration of one specific embodiment thereof, while its scope will be more particularly pointed out in the appended claims.

In the drawings, Figure 1 illustrates a lacing, or rather a double undivided lacing, to which the stiffening member has been attached; Fig. 2 shows the same after being formed into a generally cylindrical shape and before severance; Fig. 3 is a section on the line 3-3, in Fig. 2, at the line of severance;

Fig. 4 is a view, partially in section, showing the completed end with a metal tip applied, and Figs. 5, 6, 7, 8, and 9, modified forms of tips.

Referring to the drawings and to the particular embodiment of the invention therein selected for illustration, the lacing material *a* may be of any suitable or desirable formation or structure, usually, however, of tubular woven or braided fabric which may be severed into required lengths. The stiffening member *b* is here shown as in the form of a flat sheet metal blank, provided at its edges with a plurality of serrations or locking projections *b'*.

In the manufacture of the stiffened tip the lacing is held flat and the stiffened member laid thereon to engage therewith, with the serrations or locking projections securely embedded in the fabric thereof, as indicated in Fig. 1 of the drawings. With the edges of the lacing thus securely locked or embedded upon the serrated edges of the blank, the edges of the stiffening and lacing together are then turned over or rolled into a generally cylindrical formation, as shown in Figs. 2 and 3, thereby closing the portion *a'* of the lacing containing the stiffener and turning the serrated or locking points *b'* inward and giving to the lacing end the appearance of a smooth fabric-covered stiffened cylinder in which the stiffening member is entirely concealed. The lacing is then severed along a median line of severance 3-3 (Fig. 2), obtaining thereby an interiorly stiffened end of the character described for each of the severed lengths.

For obvious reasons of simplicity and cheapness in manufacture, however, I prefer in practice to form the blanks of double lengths, as shown. When used as described, severance on the line 3-3 leaves the severed lacing with both ends stiffened, the other end of the severed lacing having been previously stiffened in a like manner, and it also leaves an unsevered lacing length, the other end of which remains to be stiffened in a similar fashion. It will be readily understood that this operation which finishes the remaining end of one lacing also completes the leading end of the next lacing. The severed end of the lacing then presents an appearance generally resembling that shown in Fig. 3 and is ready for the final operation of receiving its

hard protecting tip. Such tip may be of any suitable formation, material or construction and applied in any desired way. For example, in Fig. 4 I have shown the end of the 5 lacing provided with a spherical metal tip c having an aperture at one end which is forced over the extreme end of the lacing and onto a contracted neck portion a^2 , the latter serving effectually to retain the tip in place. 10 In practice the same operation of placing the tip upon the end of the lacing may be accompanied by the formation of a contracted neck portion a^2 , the squeezing or compression of the material of the stiffener acting to 15 expand the same at the extreme end of the lacing into the hollow interior of the tip to partially or substantially fill the latter. 20 A tip of the general character described effectually prevents the severed ends of the 25 fabric material from unraveling or fraying and provides therefore a tip for the lacing end which has a durability as great as the lacing itself. Furthermore, the metal of the tip being clenched or contracted about the interior metal formation of the stiffener, any 30 tendency to loosen its hold upon the lacing end is avoided. In fact, not only does the interior stiffener act firmly to hold the tip in place, but the stiffener is more effectually 35 protected, by the presence of the tip, against distortion or collapse by being stepped on, or through other strains, and the solidity and durability of the stiffened end is thereby effectually increased. 40 It will be observed that the protection which the tip affords the fabric at the end of the lacing makes it unnecessary to fold into and within the stiffening member an extended end, as has been usual in this class of 45 devices, such end being usually doubled over for the entire length of the stiffening blank. By the use of my invention, therefore, this superfluous material is saved, which in the aggregate manufacture of these lacings results in an economy of considerable extent. 50 The absence of the inner core which is formed by this inturned lacing end, permits the completed lacing end to be rolled up into smaller diameter than usual, which, when taken particularly in connection with the suitably 55 shaped tip applied to the end thereof, provides a lacing of more pleasing appearance. The appearance of the lacing may also be improved, if desired, and its end permitted to receive a tip of smaller diameter, by giving the same a tapered formation as shown in Fig. 4. 60 It may sometimes be desirable to give the tip a more decided point than shown in Fig. 4, and in Fig. 5 I have shown a tip of substantially the same general construction, but having a bullet-shaped formation, making it more effective in finding an eyelet. If desired, the tip may be primarily formed of a 65 sheet metal blank, such as is shown in Fig. 6.

and through the use of well-known apparatus may then be clasped about and pressed upon the end of the lacing and given suitable formation in one and the same operation to provide a resulting tip such as is shown in Fig. 7. 70

The presence of the metal or other tip upon the fabric covered end gives the same a pleasing appearance in contrast to its usually dull and somber appearance. To make the tip ornamental, I may, and preferably do, form 75 the same of some brightly colored metal, such as aluminium, the latter having the advantage also of being cheap, easily worked and free from tendency to tarnish.

If desired, the tip may be made of plastic 80 or other formation, and in Fig. 8 I have shown a plastically formed tip of hard rubber or celluloid which may be pressed into shape about the expanded end of the lacing end while the material is slightly heated. 85

The tip, instead of being clasped about the extremity of the lacing end, if desired, may comprise a button-shaped piece d , as shown in Fig. 9, provided with a stem d' , the latter preferably having a slightly contracted neck. 90 Where the stiffening blanks are made up in single lengths and the severed lacing strips separately and independently attached thereto, the stem of the tip d may be rolled into the end of the stiffening member in the same 95 operation that turns the end of a lacing over and about the stiffening member, and the extremity of the end, by being compressed in and about the said stem, may be made to effectually retain the same in the desired position. 100

While I have shown and described one form of my invention for the purpose of fully illustrating the same, it is to be understood that the invention is not limited to the details here shown, or to the arrangement of parts, or to the particular mode of constructing the stiffened lacing ends here described, but that extensive modifications may be made therein within the scope of the appended 105 claims, without deviating from the spirit of my invention, and that wide departures, unnecessary to refer to, will suggest themselves to those skilled in the art. 110

I claim—

1. A lacing having an interior stiffening member, and a separate exterior metal tip. 115
2. A lacing having an interior stiffening member, and a separate exterior non-corrosive tip. 120
3. A lacing having a stiffened end provided with a contracted neck portion near its extremity and having a protecting tip upon the said extremity and retained by said contracted neck portion. 125
4. A lacing having a stiffened end tapered for substantially its entire length and provided with an exterior textile facing and a relatively hard tip. 130
5. A lacing having an interior stiffening

member for its end, and a separate hollow tip within which the extremity of said end is extended and covered and protected thereby.

6. A lacing having an interior stiffening member for its end and a separate exterior tip presenting an unbroken end surface covering and protecting the end of the tip.

In testimony whereof, I have signed my name to this specification, in the presence of two subscribing witnesses.

HENRY H. CUMMINGS.
